US0D1054264S

(12) **United States Design Patent** (10) **Patent No.:** **US D1,054,264 S**
(45) **Date of Patent:** **** Dec. 17, 2024**

(54) **TUBULAR BODY OF ELECTRONIC TORQUE WRENCH**

(71) Applicant: **KABO TOOL COMPANY**, Taichung (TW)

(72) Inventor: **Chih-Ching Hsieh**, Taichung (TW)

(73) Assignee: **KABO TOOL COMPANY**, Taichung (TW)

(**) Term: **15 Years**

(21) Appl. No.: **29/843,632**

(22) Filed: **Jun. 22, 2022**

(57) **CLAIM**

The ornamental design for a tubular body of an electronic torque wrench, as shown and described.

DESCRIPTION

FIG. 1 is a perspective view of a tubular body of an electronic torque wrench;

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top view of FIG. 1; and,

FIG. 7 is a bottom view of FIG. 1.

The broken lines show portions of a tubular body of an electronic torque wrench that form no part of the claimed design.

1 Claim, 4 Drawing Sheets
